CLAIM

The ornamental design for the golf club wood head, as shown and described.

DESCRIPTION

FIG. 1 is a top view of the new design for the golf club wood head;

FIG. 2 is a rear view of the design shown in FIG. 1;

FIG. 3 is a front view of the design shown in FIG. 1;

FIG. 4 is a bottom view of the design shown in FIG. 1; and,
FIG. 5 is a rear view of the design shown in FIG. 1.

The broken line showing is included for the purpose of illustrating and forms no part of the claimed design.
